UNITED STATES PATENT OFFICE.

JEROME ORCUTT AND CHARLES R. RICHARDS, OF BRIDGEPORT, CONNECTICUT, ASSIGNORS TO THE UNION METALLIC CARTRIDGE COMPANY, OF SAME PLACE.

MACHINE FOR CAPPING CARTRIDGE-SHELLS.

SPECIFICATION forming part of Letters Patent No. 279,497, dated June 12, 1883.

Application filed December 2, 1882. (No model.)

To all whom it may concern:

Be it known that we, JEROME ORCUTT and CHARLES RODERICK RICHARDS, both citizens of the United States, and both residents of the 5 city of Bridgeport, in the county of Fairfield and State of Connecticut, have jointly invented a new and useful Improvement in Machines for Manufacturing Paper Shells, of which the following is a full, clear, and exact description, reference being had to the accompanying drawings, in which—

Figure 1 is a top view. Fig. 2 is a vertical section through the line *a b*, Fig. 1. Fig. 3 is an enlarged view of the spring centering-guide 15 *H*, showing its several parts. Fig. 4 is a section of the slide *h* through the line *h' h'* of Fig. 3. Fig. 5 is a view, partly in section, of the dial *G*, the plate *f*, the spring centering-guide *H*, the punch *J*, and adjacent parts, and shows 20 the punch *J* having pressed the cup *I* through the hole in the dial *G* into the spring centering-guide *H*, and ready to force it onto the end of the paper-shell body which is on the pin *D*.

In the process of manufacturing paper shells 25 for shotguns, the paper bodies having been formed, the metallic cups on which the rim or flange is to be formed for the heads of the shells has to be put on the end of the paper bodies. It is desirable to partly form the flange

30 on the cups before they are put on the bodies. For the purpose of putting the cups on the bodies the cups are put in holes in a revolving dial, and the paper-shell bodies are put on pins in another revolving dial. These 35 dials, by the appliances moved by the motion of the press, are made to revolve simultaneously, so that the holes in which the cups are placed are brought one at a time directly over the bodies which are on the pins. Here- 40 tofore the flanges have not been partially formed on these cups prior to placing them on the bodies, and the holes in the dial could be made so that the cups would fit the holes, and the punch, which was brought down by the 45 motion of the press, would force the cup onto the end of the shell-body; but when, as by our improvement, the flange is partially formed, the holes in the dial must be large enough to allow the cup, with partly-formed flange, to

pass through. Consequently the cup is not 50 held sufficiently firm to insure its going accurately onto the end of the body when pressed down by the punch.

The object of this invention is to hold and direct the cup while being pressed from the 55 dial onto the end of the paper-shell body.

In the drawings, *A* is a portion of the bed of a press which supports the apparatus.

B is a plate attached to the press, with a stud *B'* therein, on which the dial *C* revolves. 60

D *D* are vertical pins in the dial, on which the paper-shell bodies *d* are placed to receive the cups *I*.

E is a standard attached to the bed of the press *A*. It supports the plate *F*, on which 65 the dial-plate *G* revolves, it being centered on the pin *e*. The dial *G* has a series of concentric holes through it, in which the partially-flanged cups are placed.

H is the spring centering-guide, by means 70 of which the cups are centered and caused to assume such position relative to the body of the shell that they shall be accurately forced upon the bodies. It is rigidly secured to the bottom of the plate *F*.

I (best seen in Fig. 5) is one of the cups placed in position to be pressed through the centering-guide.

J represents the punch in the plunger of a press, ready to force the cup through the centering-guide onto the end of the shell-body. The punch is beveled or rounded off at one side, as shown at *j*, to enable it to press the spring *K* back as the punch descends. This spring is fastened at one end to the plate *F*, 80 and its free end is so adjusted that as the cups are successively brought around by the revolving dial *G* over the hole in the centering-guide the spring *K* will impinge upon one side of the lower edge of the cup and prevent it 85 from dropping until the punch forces it into the centering-guide. The dials *C* and *G* are made to revolve simultaneously, intermittently, or otherwise, as desired, by means of ratchets and pawls, or any other suitable 90 method.

In Figs. 3, 4, and 5 we show more minutely the construction of the spring centering-guide

H. h h h are slides, which slide in and out in channels or ways cut for them in the body of the guide, as shown in Fig. 4. They are arranged radially from the center of the hole in the guide, and are normally pressed inward by the elasticity of the springs h^2 , and when so pressed inwardly their inner ends project beyond the sides of the hole. The upper edge of the inner ends of these slides is preferably, though not necessarily, beveled off, so that the cup can more easily force them back.

The operation is as follows: The cups are placed in the holes in the dial G and the bodies on the pins D, as usual. Both dials revolve in the direction shown by the arrows, or otherwise, as desired. As the cups successively approach the place where the pins and the holes coincide the spring K takes against the side of the cup, and by the pressure between the spring and the sides of the hole in the dial G the cup is supported until the punch J descends and forces the cup into the spring centering-guide H. In this guide the cup is accurately centered by reason of its sides being pressed upon by the inner ends of the slides h , and it is also adjusted horizontally by the partially-formed flange resting upon the upper beveled surfaces of the inner ends of the slides. As the plunger descends its beveled edge j presses the spring K back, releasing the cup. The cup, being pressed upon by the continually-descending plunger, presses back the slides h , and, passing through them, is received on the end of the shell-body below it, and is properly forced to its place upon it by the continued pressure of the plunger. The plunger then ascends, the dials move again, and the operation is repeated.

We do not limit ourselves to the specific arrangement of the parts shown, since they may be quite extensively varied without departing from our invention.

We claim as new and desire to secure by Letters Patent—

1. The combination, in a cartridge-making machine, of a movable dial, G, an automatic centering-guide, H, and a cup-supporting spring, K, substantially as and for the purposes set forth.

2. The combination, in a cartridge-making machine, of a movable dial, G, an automatic centering-guide, H, a punch, J, and a movable dial, C, provided with the shell-supporting pins D, substantially as and for the purposes set forth.

3. The combination, in a cartridge-making machine, of a movable dial, G, provided with holes for the reception of the heading-cups I, an automatic centering-guide, H, a punch, J, and a cartridge-supporting pin placed in line with the holes in the dial G, substantially as and for the purposes set forth.

4. The combination, in a cartridge-making machine, of a movable dial, G, the cup-supporting spring K, an automatic centering-guide, H, and a punch, J, substantially as and for the purposes set forth.

5. The combination of a movable dial, C, provided with suitable devices for holding the article to be operated upon, and which automatically moves the article in line with an automatic spring centering-guide and a punch, J, substantially as and for the purposes set forth.

Signed at Bridgeport, in the county of Fairfield and State of Connecticut, this 28th day of November, A. D. 1882.

JEROME ORCUTT.
CHARLES RODERICK RICHARDS.
